Primary Examiner — Antoine D Davis(74) *Attorney, Agent, or Firm* — Holland & Hart LLP**CLAIM**

I claim the ornamental design for the cycle indicator for fluid distribution systems, as shown and described.

DESCRIPTION

FIG. 1 is a front perspective view of the cycle indicator for fluid distribution systems according to the present design.

FIG. 2 is a front view of the cycle indicator for fluid distribution systems according to the present design.

FIG. 3 is a back view of the cycle indicator for fluid distribution systems according to the present design.

FIG. 4 is a top view of the cycle indicator for fluid distribution systems according to the present design.

FIG. 5 is a bottom view of the cycle indicator for fluid distribution systems according to the present design.

FIG. 6 is a right side view of the cycle indicator for fluid distribution systems according to the present design; and, FIG. 7 is a left side view of the cycle indicator for fluid distribution systems according to the present design.

The broken line showing of structural features is included for the purpose of illustrating non-claimed subject matter and forms no part of the claimed design.
